SLASHING MACHINE

William C. Baxter, Beverly, Mass., assignor to
United Shoe Machinery Corporation, Paterson,
N. J., a corporation of New Jersey

Application October 3, 1933, Serial No. 691,998

10 Claims. (Cl. 12—40)

This invention relates to machines for slashing sheet-stock such as that of which soles for boots and shoes are made. It is herein illustrated as embodied in a machine organized and operated in much the same manner as the machine disclosed in United States Letters Patent No. 1,124,182, granted January 5, 1915 on application of W. C. Stewart, but a machine embodying the present invention comprises certain improvements whereby it is rendered capable of operating with draw-cuts as distinguished from simple penetrating cuts according to the disclosure in said Letters Patent.

In recent years, a new kind of sheet-stock suitable for a certain type of sole has been developed. It comprises a fabricated base-material of a fibrous character, for example, wood-pulp, which is impregnated with a composition of rubber or rubber-latex. Such material is not only more flexible than sole-leather of corresponding thickness but is also more compressible than leather, although fully as satisfactory as leather with respect to tensile strength and toughness. However, because of its relatively great compressibility, flexibility and toughness it may be easily indented by a cutting edge without being actually cut thereby. Consequently, when it is attempted to cut slashes in sheet-stock having these characteristics with a slashing knife that has only a simple motion of penetration like that of a chisel, the cutting edge may not actually cut or slash the stock, or, if the knife is very sharp, it may cut slightly but at the same time expend a considerable proportion of its penetrating motion merely in indenting the stock.

To overcome this difficulty and to insure clean slashing cuts of the desired depth in sole-stock, whether of leather or of more yielding or compressible material such as that above described, the present invention provides an improved slashing machine comprising a cutting bed, a slashing knife arranged to operate against the bed, means arranged to operate the knife with simultaneous components of penetrating motion and scoring motion in an orbital path intersecting one surface of the work, and mechanism arranged to feed the work step by step and maintain it against displacement between feeding steps. Accordingly, even though the sheet-stock has characteristics that render penetration by a cutting edge dif-

ficult, or even though the cutting edge be not quite sharp, the component of motion lengthwise of the cutting edge will produce a draw-cut and insure the desired depth of penetration.

As herein illustrated, the slashing knife is affixed to a reciprocating carriage superposed upon another reciprocating carriage relatively to which the carriage first mentioned is movable. One of these carriages is operated with movements toward and from the cutting bed to provide the factor of penetration, while the other carriage is moved to and fro lengthwise of the cutting edge to provide the component required for a draw-cut. Preferably, and as herein illustrated, the mechanisms for operating these carriages are so co-ordinated as to produce a parallel orbital motion of the slashing knife.

Referring to the drawings.

Fig. 1 is a top view of a machine embodying the subject-matter of the present invention, the direction of the view being indicated by an oblique arrow above Fig. 3;

Fig. 2 is a vertical section of the upper portion of the machine;

Fig. 3 is an elevation from the same point of view as that of Fig. 2, namely, the front, but the moving parts are advanced 90 degrees from their initial positions;

Fig. 4 is a rear elevation;

Fig. 5 is a sectional view of mechanism intersected by line V—V of Fig. 3; and

Fig. 6 is a perspective view of the forepart and shank of a sole that has been slashed crosswise and represents a typical example of the operation for which the illustrated machine is designed.

With the exception of certain improvements, the elements, the organization and the mode of operation of the machine herein illustrated are like those of the machine more fully illustrated and described in the said Letters Patent No. 40 1,124,182. As in the machine shown in the above-mentioned Letters Patent, the several mechanisms are arranged in a frame 10 mounted upon a column 11 (Fig. 4). A main shaft 12 journaled in the frame 10 is provided, as heretofore, with 45 a semi-automatic friction clutch, an automatic friction brake, an eccentric 13 (Fig. 1) and a spur-gear 14, the latter (see Fig. 3) being arranged to drive a spur-gear 15 of equal size affixed to a countershaft 16 also journaled in this 50

frame. The two shafts 12 and 16 carry all the operating elements necessary to produce operation of the several automatic mechanisms.

Referring now to Fig. 2, when a sole 18 is placed in the machine it is initially flat or approximately so, as represented in full lines, but when the machine is treadled to set it in operation the sole is immediately flexed, as represented in dotted lines, before any other operation is performed thereon. The operator inserts the sole endwise with movement from left to right and preferably toe-end foremost until the toe-end thereof abuts against an adjustable stop or gauge 19 which remains stationary in the position represented in Fig. 2. The purpose of the gauge 19 is to locate the sole initially in a predetermined relation to a flat reciprocatory slashing knife 20 and a rigid, stationary cutting bed 21 between which the sole passes not only while being inserted manually but also while being fed automatically step by step from left to right after the machine has been set in operation. The work-engaging surface of the cutting bed 21 is smooth and cylindrical, and the cutting edge of the knife is straight and parallel thereto, (see Fig. 1). The act of treadling the machine to set it in operation causes upward movement of an idle roll 22 and a driven feed-roll 23, both of which extend under the sole and project beyond both side edges thereof, one in advance of the cutting bed 21 and the other behind the cutting bed. When these two rolls are raised, they bend the sole against the cutting bed 21 as represented in dotted lines, the lower surface of the sole being thereby tensioned, the more readily to be slashed or parted by the knife 20. Moreover, the idle roll 22 raises the toe-end of the sole above the level of the gauge 19 to provide for the feeding movement by which the sole is to be automatically advanced step by step over the gauge. Both of the rolls 22 and 23 remain in their upper positions until the latter half of the final cycle of operations, at which point they are restored automatically to their initial positions. The machine may be regulated by the operator, before it is set in operation, to execute any desired number of cycles and then to stop automatically.

The knife 20 is formed and arranged to cut flat individual slashes of uniform depth successively in a plane oblique to the effective plane of the cutting bed 21, and the length of its cutting edge is sufficient to insure that each slash will extend across the full width of a sole. When an insole thus slashed is subsequently incorporated into a shoe, the slashed surface will be toward the outsole, since it is desirable to place the unslashed surface toward the interior of the shoe for contact with the wearer's foot. The roll 23, preferably made of steel, is positively but intermittently driven to feed the sole and, since it does not engage the surface that will contact with the wearer's foot, it may be provided with sole-engaging teeth to render its feeding effect virtually positive. On the other hand, a complementary feed-roll 24, with which the feed-roll 23 cooperates to grip and feed the sole, is preferably shod with resilient rubber to avoid marring or indenting the surface that is to contact the wearer's foot and at the same time to furnish a powerful tractive effect both for feeding purposes and to maintain the sole against moving while the knife is operating thereon.

The feed-roll 24 is carried by a shaft 25 journaled in fixed bearings in a detachable frame

member 26 rigidly secured to the frame 10, but the toothed feed-roll 23 is journaled in a movable frame member 27 pivotally connected to the frame member 26 by trunnions 28. A compression spring 29 supported by the frame member 26 exerts its force against the movable frame member 27 through the medium of an interposed stud 30, the frame member 27 being thereby rocked on its trunnions 28 to press the feed-roll 23 against the sole after once being released from its initial position. The feed-roll 23 is initially depressed by a wedge-shaped cam 31 arranged to lift a cam-roll 32 mounted on the frame member 27, the cam being carried by a slider 33 that is operated automatically for this purpose and remains effective until released manually by treadle connections to be described.

As shown in Fig. 3, the shaft 25 that carries the rubber-covered feed-roll 24 is provided with a ratchet-wheel 35, the teeth of which are spaced one from another in accordance with the desired spacing of successive slashes to be cut by the knife 20. This ratchet-wheel is rotated intermittently by a driving pawl 36 and is constrained against reverse rotation by a spring-pressed retaining pawl 37. The driving pawl 36 is carried by a plunger 38 one end of which is guided by a fixture 39 and the other end of which is forked and straddles the counter-shaft 16 to be guided thereby. A grooved cam 40 keyed to the shaft 30 16 operates the plunger 38 which is provided with a cam-roll 41 to complete the connection. The fixture 39 contains a spring-pressed follower 42 by which the pawl 36 is pressed against the ratchet-wheel with provision for yielding as the pawl recedes from one tooth to engage the next. Rotation of the rubber-covered feed-roll 24 is communicated to the toothed feed-roll 23 by gearing shown in Fig. 4. This gearing comprises a driving gear 43 affixed to the roll-shaft 25, a broad-faced idle gear 44, an idle gear 45 arranged on one of the trunnions 28, and a driven gear 46 affixed to the shaft 47 that carries the toothed feed-roll 23. Although the driving gear 43 appears to be in meshed relation with the idle gear 45 in Fig. 4, this is not so in fact, these two gears being offset axially to clear each other, although both are in meshed relation with the broad-faced intermediate gear 44.

The slashing knife 20 is adjustably secured to a reciprocating carriage 50 by clamping bolts 51 (Fig. 2). The carriage 50 is superposed upon, and carried by, another reciprocating carriage 52. One of these carriages is operated with substantially harmonic movement toward and from the cutting bed 21 to provide a factor of penetration, and the other is operated with substantially harmonic transverse movement to provide a scoring factor while the knife is penetrating a sole lying against the cutting bed, the two components of operating movement thus imparted simultaneously to the knife being coordinated to produce a parallel motion of the cutting edge in an orbit spaced from the effective plane of the cutting bed to avoid cutting entirely through the work, and to insure a draw-cut equally deep at all points. In the illustrated construction, the carriage 52 is the one that is operated with movement toward and from the cutting bed, and the carriage 50 is the one that is reciprocated transversely to provide the scoring motion necessary for a draw-cut. The carriage 50 is mortised into the carriage 52 with tongue-and-groove connections extending parallel to the cutting edge of the knife 20. The carriage 52 is arranged to slide

in inclined guides 53 in the spaced confronting cheeks of the frame 10. An eccentric-strap 54 (Fig. 1) embracing the eccentric 13 imparts substantially harmonic motion to the carriage 52 by 5 a pivot-pin 55 (Fig. 2).

Motion for reciprocating the carriage 50 transversely is communicated positively thereto in timed relation to the to-and-fro motions of the carriage 52. For this purpose, a grooved block 10 56 is affixed to the under side of the carriage 50, the groove being parallel to the path of the carriage 52 (see Fig. 1). A slider 57 arranged in this groove is mounted on a pivot-stud 58 carried by a two-armed lever 59. The lever is mounted upon 15 a fulcrum-pin 60 secured in a web of the frame 10. The other arm of the lever 59 is pivotally connected to a link 61 operated by a lever 62. This lever is mounted on a fulcrum-pin 63 (Fig. 5) inserted into the frame 10. A segmental gear 20 64 formed on the lever 62 receives operating motion from a rack 65 formed on a member 66 carried by a slide 67 arranged in guides 68 affixed to the frame 10. A cam-roll 69 carried by the slide 67 receives harmonic operating motion from a 25 circular eccentric cam-groove 70 formed in the same member that provides the cam 40 hereinbefore described. The non-integral construction of the elements 66 and 67 is due to utilization of parts originally designed to provide a yieldable 30 connection in machines such as that set forth in said Letters Patent No. 1,124,182, but, for the purposes of the present invention these two elements are virtually one in operation and effect. Accordingly, as illustrated in Fig. 5, a tubular 35 filler 71 takes the place of a compression-spring that was originally intended to be interposed between the elements 66 and 67 to provide the yieldable connection above mentioned. For present purposes, the filler 71 and the parts by which it 40 is secured maintain the elements 66 and 67 rigidly in constant relation so that the transverse motion of the slashing knife 20 will be positive under all conditions. Referring to Figs. 1 and 2, although the grooved block 56 partakes of 45 the reciprocations of the carriage 52 toward and from the cutting bed 21, the length of the block is sufficient to maintain the operating connection between the transversely movable carriage 50 and the operating lever 59.

50 As in the organization shown in the Letters Patent above mentioned, the counter-shaft 16 is provided with a cam 72 (Fig. 2) the purpose of which is to operate a regulatable mechanism by which the machine is automatically stopped upon completion of a predetermined but variable number of cycles of operation. This cam reciprocates a lever 73 the fulcrum of which is a stationary stud 74 secured to the frame 10. This lever carries a pawl 75 (Figs. 1, 3 and 4) arranged to turn a ratchet-wheel 76 a distance corresponding to one tooth for each cycle of the slashing knife. The ratchet-wheel is loosely mounted on a spindle 77 and is influenced by a torsion spring 78 and thereby restored automatically to an initial position whenever it is released from a retaining pawl (not shown). The spindle 77 is provided with a combined knob and dial 79 at its upper end whereby it may be manually depressed against the force of a compression-spring 80 to release it from the ratchet-wheel and by which it may also be turned relatively to the ratchet-wheel when so released, this device constituting a regulator by which the operator may set the machine to be automatically stopped when it has 60 executed a predetermined number of cycles. A

tripping finger 81 affixed to the lower end of the spindle 77 is provided with a pin (not shown) that may enter any one of a circular series of holes 80 formed in the ratchet-wheel, the number and spacing of the holes corresponding to those 5 of the teeth of the ratchet-wheel. The angular position of the finger 81 with respect to the ratchet-wheel may be varied by turning the knob 78 whenever the spindle 77 is released from the ratchet-wheel as above described, but the finger 10 81 is locked relatively to the ratchet-wheel whenever the locking pin enters one of the holes 80. Thus, after once setting the finger 81 at the desired position with respect to the ratchet-wheel, a predetermined number of operating strokes of 15 the pawl 75 will be required to turn the finger to a position where it will abut against the lower end of a tripping rod 82, shown in Fig. 4. In the final cycle determined by the preliminary setting of the knob 78, the finger 81 will displace 20 the rod 82 endwise against the force of a compression-spring 83 and thereby set in motion several automatic mechanisms, one of which depresses the roll 22 to its initial position, one of 25 which depresses the toothed feed-roll 23 to its initial position, and one of which disconnects the driving clutch on the main shaft 12 and applies a brake to arrest the rotation of the main shaft at or near a point corresponding to full retraction of the knife-carriage 52. 30

The upper end of the tripping rod 82 carries a block or striker 84 arranged to break a toggle 85, 86 which, when the machine is in operation, is maintained in a straightened position by a tension-spring 87. The toggle member 85 is connected to the frame 10 by an anchoring pivot 88, while the toggle member 86 is connected to a lever 89 by a pivot-pin 90. The lever 89 is connected to the frame 10 by a fulcrum-pin 91 and is also connected to the upper end of a link 92 by a pivot-pin 93. A tension-spring 94 anchored to the frame 10 engages the pivot-pin 93 to exert a downward pull thereon but, when the link 92 is raised above its initial position shown in Fig. 4 to set the machine in operation, the lever 89 45 straightens the toggle 85, 86 which then remains straightened so long as the machine is in operation notwithstanding the downward pull of the spring 94. 45

The pivot-pin 90 carried by the lever 89 also 50 forms an operating connection between the toggle 85, 86 and a yoke 95 in which the roll 22 is journaled. This yoke is connected to the frame 10 by trunnions 96. The toggle 85, 86 is thus rendered effective to maintain the roll 22 in its operative position to which it may be raised only by upward movement of the link 92, but, when the striker 84 breaks the toggle, the spring 94, which is stronger than the spring 87, becomes effective 55 to maintain the roll 22 in its lower position while 60 the machine is at rest.

The lever 89 is also effective to cause operation of the slide 33 (Fig. 2) whereby the cam 31 is moved in a direction to depress the toothed feed-roll 23 to its initial position. For this purpose, 65 the lever 89 is provided with an arm 97 from which motion is communicated by a link 98 to an arm 99 and thence to a toggle (not shown) by which the cam slide 33 is operated as in the organization illustrated in the Letters Patent above 70 mentioned.

When the lever 89 is released in consequence of operation of the striker 84, the link 92 is immediately drawn down to the position shown in Fig. 4 by the spring 94, this motion of the link 75

being communicated to a lever 100 by a pin 101 affixed to the rod. When the lever 100 is thus actuated it initiates the operation of automatic stopping mechanism by which a driving clutch 48 and a friction-brake 49 on the main shaft 12 are controlled to arrest the shaft at a predetermined point in its cycle. The construction and operation of this automatic stopping mechanism are similar to those of the corresponding mechanism illustrated and described in United States Letters Patent No. 1,864,631, granted June 28, 1932 on my application. A characteristic of this mechanism is that although the operator may set the machine in operation by raising a treadle-rod 34, the shaft will stop at the completion of any predetermined number of cycles whether or not the operator releases the treadle-rod.

The specimen sole represented in Fig. 6 has a series of thirteen transverse slashes 105 and represents a typical example of work for which the illustrated machine is designed. Assuming that it is desired to use the machine to form a series of thirteen slashes as represented in this figure, the operator will first depress the knob 78 and then turn it to a position that will bring the numeral 13 of a scale carried by the knob to a corresponding position in register with a stationary index point 106 (Fig. 1). The machine is thus made ready to operate without any further effort on the part of the operator except to insert a sole and depress a treadle (not shown) to raise the treadle rod 34. When the sole is inserted, it is supported not only by the rolls 22 and 23 but also by a stationary supporting table 107 (Fig. 2). Having inserted the sole far enough to place the toe, end thereof against the gauge 19, the operator depresses the treadle, the first effect of which is to raise the rolls 22 and 23 as hereinbefore described. The final stage of upward movement of the treadle rod 92 renders the driving clutch 48 operative, whereupon the shafts 12 and 16 are set in operation which continues until they have executed thirteen cycles. During the thirteenth cycle, the striker 84 (Fig. 4) breaks the toggle 85, 86 at that stage when the slashing knife has completed its thirteenth slashing motion but before it has been fully retracted from the cutting bed 21. Now, before the rotation of the shafts is arrested, the knife-carriage 52 returns to its initial position (full retraction) and thereby picks up and carries with it the cam-slide 33 by which the toothed feed-roll 23 is depressed. The picking up of the cam-slide 33 is due to the final movement of the lever 89 whereby the lever 99 is operated. The final movement of the lever 89 also actuates the lever 100 by which a toggle 102 is straightened to transmit the motion of a cam (not shown) to a lever 103. When the lever 103 is thus rocked on its fulcrum-pin 104 it releases the clutch 48 and applies the brake 49.

Having thus described my invention, what I claim as new and desire to secure by Letters Patent of the United States is:

1. A machine for slashing sheet-stock comprising a cutting bed, a slashing knife arranged to operate against said bed, means arranged to operate said knife with simultaneous components of penetrating motion and scoring motion in an orbital path intersecting one surface of the work, and mechanism arranged to feed the work step by step and maintain it against displacement between feeding steps.

2. A machine for slashing sheet-stock comprising a cutting bed having a convex work-sustaining surface, means arranged to bend a work-piece

against said surface and thereby tension the outcurved surface of the work-piece, a reciprocatory knife arranged to cut a slash in the outcurved surface of the work-piece so bent, and mechanism arranged to operate said knife with simultaneous components of penetrating motion and motion lengthwise of its cutting edge.

3. A machine for slashing sheet-stock comprising a slashing knife and a cutting bed arranged in a relation to produce an inclined slash in a work-piece lying between them, and means arranged to operate the knife with penetrating motion and scoring motion so compounded as to produce parallel motion in an orbital path intersecting one surface of the work.

4. A machine for slashing sheet-stock comprising a cutting bed having a convex work-sustaining surface, means arranged to bend a work-piece against said surface, mechanism arranged to feed a sole step by step, a knife having a straight cutting edge arranged to cut slashes successively in a work-piece so fed, and mechanism arranged to operate said knife with an orbital motion comprising simultaneous components of penetrating motion and motion lengthwise of its cutting edge.

5. A machine for slashing sheet-stock comprising a cutting bed, mechanism arranged to feed a work-piece step by step, a knife having a straight cutting edge arranged to cut slashes successively in a plane oblique to the work-sustaining surface of said cutting-bed, and mechanism arranged to operate said knife with an orbital motion comprising simultaneous components of penetrating motion and motion lengthwise of its cutting edge.

6. A machine for slashing sheet-stock comprising a knife and a cutting bed relatively movable to and fro to cut a series of slashes successively in a work-piece located between them, mechanism arranged to operate one of them with a component of penetrative movement and one of them with a simultaneous component of transverse movement, and mechanism arranged to feed the work-piece step by step transversely of the slashes while said knife is out of the work to place a series of unslashed portions thereof successively in the path of the knife.

7. A machine for slashing sheet-stock comprising a cutting bed, two reciprocatory carriages one of which is superposed upon and carried by the other and movable crosswise relatively thereto, a knife secured to said superposed carriage, and means arranged to reciprocate said carriages, in relatively transverse directions with substantially harmonic motions compounded to carry the knife in an orbital path intersecting one surface of the work.

8. A machine for slashing sheet-stock comprising a cutting bed, two reciprocatory carriages one of which is superposed upon, and carried by, the other and movable relatively thereto, a knife secured to said superposed carriage, mechanism arranged to operate said other carriage with movement toward and from said cutting-bed, mechanism by which said superposed carriage is moved transversely of the path of said other carriage while the knife is penetrating a work-piece lying against the cutting bed, and work-feeding means by which the work-piece is advanced step by step and maintained against moving while said knife is operating on the work-piece.

9. A machine for slashing sheet-stock comprising a fixed cutting bed, mechanism arranged to

feed a work-piece step by step to place a series of portions thereof successively at a fixed point of operation on said cutting bed, a knife arranged to cut individual transverse slashes successively in the portions stationed at said fixed point, and mechanism by which said knife is operated to cut while the work is stationary with an orbital motion comprising components of penetrating motion and simultaneous components of motion lengthwise of its cutting edge.

10

10. A machine for slashing sheet-stock comprising a cutting bed, a knife arranged to cut slashes successively in a work-piece lying against said cutting bed, two cooperative feed-rolls one of which is movable toward and from the other to grip and release the work-piece, mechanism by which both of said feed-rolls are driven intermittently to feed the work-piece, and mechanism by which said knife is operated.

5 WILLIAM C. BAXTER. 10
